UNITED STATES PATENT OFFICE.

THEOPHILUS W. ALEXANDER, OF BURLINGTON, IOWA.

OIL-CAN.

No. 922,996.

Specification of Letters Patent.

Patented May 25, 1909.

Application filed January 23, 1909. Serial No. 473,838.

To all whom it may concern:

Be it known that I, THEOPHILUS W. ALEXANDER, a citizen of the United States, residing at Burlington, in the county of Des Moines and State of Iowa, have invented certain new and useful Improvements in Oil-Cans; and I do hereby declare the following to be a full, clear, and exact description of the invention, such as will enable others skilled in the art to which it appertains to make and use the same.

My invention relates to oil cans or receptacles wherein air pressure is employed for forcing the liquid from the can or receptacle into a lamp or other vessel.

The objects of my invention are to simplify the construction, reduce the cost of manufacture and provide for readily cleaning and repairing the check valve used in connection with the means for forcing air into the receptacle. Any suitable means, such as a blow-pipe or compression-bulb may be employed for forcing air into the can.

In carrying out my invention, I place the check valve in a straight tube section detachably connected below the cap for the filling nozzle and around a port or opening in said cap, and secure said tube to said cap by a flexible connection. By this arrangement it is possible to remove the tube section carrying the valve from the can with the cap of the filling nozzle and further facilitate the cleaning or repairing of the valve by disconnecting said tube section from said cap. The check valve is placed at the lower end of the tube section and is what may be termed a sensitive valve, that is one which is normally open as distinguished from a gravity valve or one which is normally closed.

The invention also consists in the features of construction and combinations of parts hereinafter described and specified in the claims.

In the accompanying drawing, illustrating the preferred embodiment of my invention: Figure 1 is a top plan view of a can or receptacle constructed in accordance with my invention. Fig. 2 is a vertical section on the line $x-x$ of Fig. 1, and, Fig. 3 is an enlarged central vertical section through the cap and for the filling nozzle, the tube section carrying the valve and the lower end of the blow-pipe.

Referring more particularly to the drawing, 1 designates a can or tank having its top 2 provided with three ports or openings. A

discharge tube 3 is engaged with one of the openings 4. The second opening 5 serves as the filling nozzle, while the third port 6 is a vent opening normally closed by a stopper 7 60 preferably attached to the top of the can by a chain 8 or other suitable flexible connection.

The usual screw cap 9 is employed for closing the filling nozzle, but in this instance said cap is provided with an opening 10 in which is fixed a depending (preferably tapering) thimble 11. The short tube section 12 carrying the check valve 13 is detachably connected around the lower end of said thimble 70 and is attached to the cap by means of the chain 14 or other suitable flexible connection. The valve preferably consists of a disk 15 arranged in a cage 16 at the lower end of said tube section. By reason of its arrangement, it will be seen that the valve is normally arranged in a lowered or open position. The cage 16 has a large opening 17 in its lower end and comparatively small ports 18 in its sides. Air enters, or is forced into 80 the can or receptacle through the lateral ports, but the compressed air in the receptacle acts upon the valve through the large bottom opening whereby the valve is rendered very sensitive and reliable. The blow-pipe 19 is introduced into the upper end of the thimble 11.

In using my device, air is forced by the blow-pipe into the can or receptacle to create a pressure upon the upper surface of the oil or 90 contents of the can, the valve resting at the bottom of its cage and permitting the air to enter via the lateral ports in said cage. The pressure thus introduced into the receptacle will effect the lifting or forcing of the oil up 95 through the discharge tube 3 into a vessel for its reception. When the operator ceases to force air into the can, the air pressure already therein will act upon the valve through the large bottom opening in its cage, and will 100 raise said valve and seat it over the lower end of the passage through the tube section 12, thereby preventing escape of air through the blow-pipe. As the delivery of the oil or 105 contents of the receptacle continues, the air pressure will generally decrease and finally allow the valve to drop down to its normal lowered position. If, however, it is desired to stop the flow of the oil before the air pressure is exhausted, this may be easily done by 110 simply removing the stopper 7 from the vent opening thereby permitting the escape of air

remaining in the receptacle, and instantly stopping the flow of the oil from the discharge tube.

I claim:

- 5 1. The combination, with a receptacle of the character described having a discharge tube, of a tapered thimble fixed in an opening in the top of said receptacle, a detachable straight tube section fitted around the outside of said thimble within the receptacle and carrying a check valve in its lower end, and a detachable tube, through which air may be forced into the receptacle, fitted in the inside of said thimble and arranged on the outside 10 of the receptacle.
- 10 2. The combination, with a receptacle of the character described having a discharge

tube and a filling nozzle, of a cap for said nozzle having an opening therein, a tapered thimble fitted in said opening, a detachable straight tube section fitted around the outside of said thimble within the receptacle and carrying a check valve in its lower end, flexible connection between said tube section and cap, and a detachable tube, through which air may be forced into the receptacle, fitted in the inside of said thimble and arranged on the outside of the receptacle. 20 25

In testimony whereof, I affix my signature, in presence of two witnesses.

THEOPHILUS W. ALEXANDER.
